CHARGING STAND FOR BATTERY OPERATED APPLIANCE

Dominic J. De Fano, Palatine, and Robert I. Kallman,
Elburn, Ill., assignors to Sunbeam Corporation, Chi-
cago, Ill., a corporation of Illinois

Filed July 12, 1968, Ser. No. 12,730

Term of patent 14 years

Int. Cl. D4—02

U.S. Cl. D4—16

Fig. 2.

FIG. 1 is a front perspective view of a charging stand for a battery operated appliance embodying our new design;

FIG. 2 is a top plan view thereof;
 FIG. 3 is a side elevational view thereof; and
 FIG. 4 is a rear elevational view thereof.

We claim:

The ornamental design for a charging stand for battery operated appliance, as shown.
